UNITED STATES PATENT OFFICE.

WILLIAM M. STEVENSON, OF CLEVELAND, OHIO.

NON-FREEZING FORCE-PUMP.

SPECIFICATION forming part of Letters Patent No. 329,234, dated October 27, 1885.

Application filed September 12, 1884. Serial No. 142,902. (No model.)

To all whom it may concern:

Be it known that I, WILLIAM M. STEVENSON, a citizen of the United States, residing at Cleveland, in the county of Cuyahoga and State of Ohio, have invented certain new and useful Improvements in Non-Freezing Pumps, of which the following is a specification, reference being had to the accompanying drawings.

My invention relates to double-acting force-pumps for wells, cisterns, and sinks; and the invention consists in certain improvements in the construction and arrangement of the parts, whereby the operation of such pumps is rendered more perfect and the objections heretofore existing to their use are obviated.

My pumps are so constructed as to give a continuous and unbroken flow of water when using a hose or nozzle, and will work with like facility in winter and summer. Their construction is comparatively simple. They are easily operated, and occupy but small space compared with other descriptions of force-pumps.

In the accompanying drawings, forming a part of this specification, Figure 1 is a sectional view. Figs. 2, 3, 4, 5, 6, 7, 8, 9 are detached detailed views of some of the parts. Fig. 10 is a sectional view of the piston I, and 30 shows the several parts of the valve J' therein. Fig. 11 is a detached plan view of the slide A', rollers a, and part of the handle B. Fig. 12 is a detached side elevation of the valve J and a part of the piston-rod A. Fig. 13 is a 35 plan view of the valve J detached from the pump, and shows the piston-rod A in section.

The letter A indicates a piston-rod, the upper end of which is attached to a slide, A', provided with two or more friction-rollers, a, 40 and which is pivoted to the handle B. This slide is made of two pieces of metal, one of which is placed on each side of a guide-rod, C, the lower end of which is secured to a bracket, C'. This bracket is attached to the top of a 45 pipe, D, and extends backwardly and forms the support of a toggle, b, the lower end of which is pivoted thereto by the pivot b', and the upper end thereof to the handle B at b'. A spout, E, having a hollow boss, e, which 50 encircles the pipe D, is screwed fast to the top of the pipe D', from which it receives its supply of water. The pipes D and D' are screwed

fast into the air-chamber F, which has a flange, f, by means of which it is bolted down to the platform or well-cover f'. From the under 55 side of the air-chamber F are pipes D² and D³, which extend in a downward direction, and are screwed into an intermediate chamber or connection, G, on the top of which is secured the cylinder D'', through which passes the 60 piston-rod A, having a piston, d, fitted to the cylinder D''. A pipe, E', is screwed into the bottom of the connection G, and extends downwardly to a valve-casing, H, inclosing a valve, J, which slides freely on the piston-rod A. 65 This valve consists of a metal cup provided with leather packing, and with deep serrations all around the top, which hook over inwardly, and thus secure in a permanent manner and at a proper distance below the top of the valve 70 the leather packing within, so that when the valve J strikes or rests against the lower end of the pipe E' on the upstroke of the piston, water then rising upward readily passes through and between the serrations and into 75 and through the connecting-pipes above, and from thence out. On stoppage of the upstroke the valve J returns to the lower part of valve-casing H, thus stopping or relieving the strain that would otherwise be on the cylinder below, 80 and its foot-valve and piston, and preventing the destructive force of (what is termed) the "water-hammer," and so permitting the water to drain gradually from the pump. The rod A extends through the pipe E' and the 85 valve-casing H down into the cylinder E'', where a piston, I, is secured to its lower extremity by means of nuts i and i', which are fitted to a screw-thread on the lower end of the piston-rod. This piston forms a hollow 90 cylinder, open at the bottom and perforated on top, and is furnished with a valve, I', through which the water passes, the details of which are shown in Fig. 10 of the drawings. At the bottom of the cylinder E'' there is a 95 coupling, K, attached thereto by means of the inclines l and lugs c, as shown in Figs. 7, 8, 9. The bottom of the valve-casing H and top of cylinder E'' are connected at K' by means of inclines l and lugs c, in the same manner as 100 coupling K, or in any other convenient way. The cylinder D'' has a flange, d'', near the bottom, with openings cut on its opposite sides for the passage of the pipes D² D³. A packing-

ring of leather is placed around the bottom of the cylinder D", between the flange d^2 and the top of the connection G, whereby a watertight joint is secured between the two.

5 Having described my invention, what I desire to secure by Letters Patent and claim is—

1. The combination of spout E, having hollow boss e, pipes D D', and bracket C, with toggle b, handle B, slide A', having (two or 10 more) friction-rollers, a, and guide-rod C, with piston-rod A, substantially as described, and for the purposes set forth.

2. In a force-pump, the cylinder D", the piston d, the intermediate detachable cham-

ber, G, the pipes D², D³, and E', and valve-casing H, in combination with the valve J, consisting of a serrated metal cup having inwardly-projecting points inclosing leather packing-rings adapted to slide up and down over the piston-rod A, as described, and for 15 the purposes set forth.

In testimony whereof I affix my signature in presence of two witnesses.

WILLIAM M. STEVENSON.
